UNITED STATES PATENT OFFICE

NOEL DEISCH, OF WASHINGTON, DISTRICT OF COLUMBIA, ASSIGNOR TO LOCKE INSULATOR CORPORATION, OF BALTIMORE, MARYLAND, A CORPORATION OF MARYLAND

CONDUCTOR-RELEASING CLAMP

Application filed November 11, 1929, Serial No. 406,423.

The invention relates to clamps for the suspension of the conductors forming part of high tension transmission lines.

The principal object of the invention, generally stated, is to provide a clamp adapted for suspending a conductor from the usual towers or other equivalent supports and characterized by capability of releasing its gripping action upon the conductor in the event of breaking thereof or excessive strain thereupon at one side of a tower, the result being that the conductor may slip with respect to one or more of the clamps and the strain be distributed instead of it all coming upon a single tower with possible damage thereto.

It is well known that under certain climatic conditions there may be a thick and very heavy accumulation of sleet or ice upon a transmission line and where the spans are very long it is possible that this great weight may cause breakage of the conductor or at least such tremendous sagging as to exert an excessive strain upon the adjacent tower. The same condition may occur as the result of high wind at one side or the other of a ridge and, indeed, from other causes. It is with these facts in view that I have devised the present invention which has for an important object the provision of a suspension clamp which is adapted and intended to be hung from a string of insulators, as is customary, and which will under ordinary circumstances grip the conductor with absolute firmness but which will under some circumstances release its holding action and permit the conductor to slip through.

Another important object is to provide a clamp of this character which may be described as trigger-operated, that is to say one in which the holding action will be maintained until the clamp and the string of insulators suspending the same have been pulled by strain on the conductor into or beyond a certain predetermined inclination whereupon release occurs, not gradually, but suddenly and completely so that there will be a quick release.

Another object of the invention is to provide a clamp of this character which after release and after distribution of strains

on the conductor will automatically regrip the conductor so that manual setting will be unnecessary at that particular time.

Another object is to provide a clamp in which a certain freedom of movement or swinging of the clamp itself and supporting insulators may take place, as for example during ordinary windy weather conditions, or expansion and contraction of the conductor in a span affected by local temperature variations without releasing it, it being necessary that the inclination exceed a certain safe limit before release occurs.

A further object is to provide a clamp of this type in which the parts cannot become disassociated and lost when release takes place, adequate means being provided for always holding the parts together under every condition.

A still further object is to provide a clamp of the character described in which there is no wear upon any of the operating faces under normal conditions, there being consequently no diminution of the clamping action resulting from prolonged use.

An additional object is to provide a clamp of this type which will be simple and inexpensive to make, easy to apply or use, positive in action, efficient and durable in service, and a general improvement in the art.

To the attainment of the foregoing and other objects and advantages, the invention preferably consists in the details of construction and the arrangement and combination of parts to be hereinafter more fully described and claimed, and illustrated in the accompanying drawings in which:

Figure 1 is a side elevation of my clamp showing it in normal or gripping relation to the conductor,

Figure 2 is a similar view showing the parts moved into released position,

Figure 3 is a top plan view,

Figure 4 is an end elevation,

Figure 5 is a vertical cross sectional view taken on the line 5—5 of Figure 1, and

Figure 6 is a vertical cross sectional view taken at substantially the center or on the line 6—6 of Figure 1.

Referring more particularly to the draw-

100

ings I have shown my clamp as comprising upper and lower clamping members 10 and 11 which may be and preferably are counterparts so as to reduce the cost of manufacture and the quantity of parts needed to be kept in stock by the manufacturer or user. Each of these members is shown as an elongated body with a transversely curved conductor receiving seat 12 therein for the reception of the conductor 13. Preferably the ends of the seats are flared outwardly as shown so as to prevent the bringing of any abrupt bending strains upon the conductor in the event of vibration of the line as will inevitably occur in actual practice. Each member 10 and 11 is formed with a yoke 14 straddling the other, and as the members 10 and 11 are counterparts and reversed the yoke on the lower one has its open end directed upwardly whereas the yoke on the upper one has its open end directed downwardly. These yokes are U-shaped in form so as to straddle the respective clamping members and they are engaged between outstanding lugs 15 on the respective clamping members for preventing relative longitudinal movement thereof. Extending through the closed bight portion of each yoke is a fulcrum pin 16 upon which is engaged the apertured end of a leaf or plate spring 17 which has its other end engaged within a loop or link 18 carried by a lug 19 on the associated and adjacent clamping member.

The means for holding the members 10 and 11 in clamping relation upon the conductor 13 is further shown as including cam levers 20 having cam faces 21 thereon and formed with oppositely extending trunnions 22 pivotally engaged within notches 23 in the inner faces of the arms of the yokes. The cam faces 21 of the levers are adapted to bear upon the adjacent surfaces of the clamping members 10 and 11 within the confines of the yokes 14, and the free ends of the levers extend toward the transverse center of the clamp, these free or inner ends being engaged beneath or against the inner faces of the springs 17 and having lateral projections 24 for a purpose to be described. Clearly the compression of the springs 17 upon the inner ends of the levers 20 will urge these inner ends toward the conductor so that the cam faces 21 will bear upon the top and bottom of the clamping members 10 and 11 respectively and urge them into clamping relation to the conductor so that an efficient gripping action will be assured.

The suspension means for this clamp assembly is here represented as comprising a pair of links 25 apertured at their other ends as shown at 26 for passage of a suitable securing element by means of which the entire assembly may be suspended from a string or chain of suspension insulators. As the lower ends of the links will not interfere with

the lower spring 17 they are represented as connected by a transverse pin 27 though this is an immaterial detail as it is conceivable that the links might be cut off above the lower spring 17 if preferred. The means for releasing the clamping action is shown as comprising a double ended cam or pair of cams 28 suitably secured to the inner faces of the links 25, as by rivets or other securing elements 29, these cams being further provided with trunnions 30 projecting into an opening defined by mating semicylindrical recesses 31 in the clamping members. Attention is directed to the fact that this trunnion arrangement or pivotal mounting is such that the axis of the links will extend through the center of the conductor, thereby permitting the clamp to accommodate itself to line vibrations without producing any noticeable bending or abrading action on the conductor at the ends of the clamping members.

To assemble the clamp, the two jaws or clamping members 10 and 11 are brought together over the conductor, after which the levers 20 are inserted by engaging the trunnions 22 thereof within the lower ends of the bearing recesses or notches 23, the levers being at this time held substantially vertically at the entrances to the notches or recesses. Of course the springs 17 are initially assembled upon the pins 16 upon which they are held by the upset ends thereof. The springs are then so positioned as to bring them over the levers 20, that is to say one above the upper lever 20 and the other below the lower member 20. Any suitable assembling clamp, not shown, may then be utilized for drawing the springs down or toward the conductor so that the loops 18 may be engaged over their free ends. The assembling clamp is of course then removed and it will be found that the action of the springs 17 upon the cam levers 20 will maintain these cam levers in such position that the cam surfaces 21 thereof bearing against the adjacent outer surfaces of the clamping members will hold these clamping members in firm engagement upon the conductor. This is the relation of the parts under normal circumstances and even when there is a certain angular position of the links with respect to the clamp as might be brought about by swaying of the conductor under the influence of the wind or various other circumstances unnecessary to enumerate. If, however, there should be a breakage of the conductor or if there is any other condition, such as an accumulation of ice and snow on one or more spans, which unusual condition results in the bringing of an excessive strain upon the conductor at either side of the clamp, it will be apparent that the suspension links 25 will swing upon the trunnions 30 into a position of considerable angularity as clearly indicated in Figure 2. When this occurs

the cams 28 will engage against the laterally extended inner ends 24 of the cam levers and force them outwardly against the resistance of the springs 17. As these cam levers thus 5 move apart the distance between the bearing faces or cam surfaces 21 thereof and the center line of the conductor will be increased, thereby permitting the clamping members 10 and 11 to move apart and release their grip 10 upon the conductor which may then slip through until the strains upon it have become uniformly distributed. This condition may 15 take place at several suspension points and it is clear that equalization will be assured. 15 Just as soon as the excessive strain has been relieved and the suspension links resume a position approximating the normal the cams 28 will disengage the inner ends of the cam levers so that the springs 17 will again exert 20 their power and move the cam levers into their clamp engaging positions, thereby reffecting the desired clamping action upon the conductor. It will consequently be seen that 25 the action of releasing and regripping is entirely automatic and governed by conditions. It is believed that the construction, operation and advantages should be readily apparent from the foregoing without further explanation.

30 While I have shown and described the preferred embodiment of the invention, it should be understood that the disclosure is merely an exemplification of the principles involved as the right is reserved to make all such changes 35 in the details of construction as will widen the field of utility and increase the adaptability of the device provided such changes constitute no departure from the spirit of the invention or the scope of the claims hereunto 40 appended.

Having thus described the invention, I claim:

1. In a conductor supporting clamp, the combination of upper and lower clamping members disposable against a conductor, suspension means for the assembled clamping members, cam means carried by the clamping members, spring means urging said cam means into position for maintaining the 45 clamping members in clamping relation upon the conductor.

2. In a conductor supporting clamp, the combination of upper and lower clamping members disposable against a conductor, suspension means for the assembled clamping members, cam means carried by the clamping members, spring means urging said cam means into position for maintaining the clamping members in clamping relation upon 50 the conductor, and means operable upon relative swinging movement of the suspension means beyond a predetermined extent for neutralizing said spring means.

3. In a conductor supporting clamp, the 55 combination of upper and lower clamping

members disposable against a conductor, suspension means for the assembled clamping members, cam means carried by the clamping members, spring means urging said cam means into position for maintaining the 70 clamping members in clamping relation upon the conductor, and means operable upon relative swinging movement of the suspension means beyond a predetermined limit for moving said cam means into ineffective position in opposition to said spring means.

4. In a conductor supporting clamp, the combination of upper and lower clamping members disposable against a conductor, suspension means for the assembled clamping 80 members, cam means carried by the clamping members, spring means urging said cam means into position for maintaining the clamping members in clamping relation upon the conductor, and cam means on the suspension means engageable with said first named cam means for rendering the same ineffective upon relative swinging movement of the suspension means beyond a predetermined 85 extent.

5. In a conductor supporting clamp, upper and lower clamping members, cam means carried by each clamping member and engageable with the other for urging the clamping members toward each other, spring means 90 engaging said cam means for rendering the same normally effective, suspension means for the clamp assembly movable with respect thereto, and means on the suspension means for releasing said cam means upon movement 95 of the suspension means with respect to the clamp assembly beyond a predetermined extent.

6. In a conductor supporting clamp, upper and lower clamping members, cam means carried by each clamping member and engageable with the other for urging the clamping members toward each other, spring means 100 engaging said cam means for rendering the same normally effective, suspension means for the clamp assembly movable with respect thereto, and means on the suspension means for releasing said cam means upon movement 105 of the suspension means with respect to the clamp assembly beyond a predetermined extent, said suspension means being pivotally connected with the clamping members.

7. In a conductor supporting clamp, upper and lower clamping members, cam means carried by each clamping member and engageable with the other for urging the clamping members toward each other, spring means 110 engaging said cam means for rendering the same normally effective, suspension means for the clamp assembly movable with respect thereto, and means on the suspension means for releasing said cam means upon movement 115 of the suspension means with respect to the clamp assembly beyond a predetermined extent, said suspension means with respect to the clamp assembly beyond a predetermined extent, said suspen-

- sion means being pivotally connected with the clamping members and having its axis intersecting the longitudinal axis of the conductor.
- 5 8. A conductor supporting clamp comprising a pair of clamping members disposable against the conductor, cam levers pivoted on each clamping member and engaging the other, spring means carried by each 10 clamping member and engaging the adjacent clamping lever for maintaining the clamping levers in effective position for forcing the clamping members toward each other, suspension means pivotally suspending the 15 assembled clamping members, and means operable upon movement of the suspension means beyond a predetermined extent for moving said cam levers into ineffective position.
- 20 9. A conductor supporting clamp comprising a pair of clamping members disposable against the conductor, cam levers pivoted on each clamping member and engaging the other, spring means carried by each 25 clamping member and engaging the adjacent clamping lever for maintaining the clamping levers in effective position for forcing the clamping members toward each other, suspension means pivotally suspending the 30 assembled clamping members, and means operable upon movement of the suspension means beyond a predetermined extent for moving said cam levers into ineffective position, said means comprising cams on the 35 suspension means and projections on the cam levers in the path of movement thereof and engageable thereby.
- 40 10. A clamp of the character described comprising a pair of clamping members engageable against a conductor and each formed with a yoke straddling the other, a cam lever pivoted within each yoke and engaging the adjacent clamping member, a leaf spring carried by each clamping member and having its 45 intermediate portion engaging the adjacent cam lever, suspension means for the assembled clamping members, and means carried by the suspension means engageable with said cam levers for moving the same into ineffective position against the resistance of 50 said springs.
- 55 11. A conductor supporting clamp comprising upper and lower clamping members disposable against a conductor, each clamping member being provided with a yoke straddling the other, cam levers pivoted within said yokes and having cam surfaces normally engaging the adjacent clamping members, a leaf spring carried at one end by 60 each yoke, means for anchoring the other ends of said springs to the adjacent clamping members, the inner ends of said cam levers being engaged inwardly of said springs and having portions projecting laterally 65 thereof, suspension means pivotally 120 125 130
- connected with the assembled clamping members, and cam means on the suspension means engageable with the projecting portions of the inner ends of said cam levers for moving the same outwardly into ineffective position upon relative swinging movement of the suspension means beyond a predetermined angular position.
- 70 In testimony whereof I affix my signature.
